CLAIM

The ornamental design of a pedestal with ornament holder, as shown and described.

DESCRIPTION

FIG. 1 is a perspective view showing my new pedestal with ornament holder;

FIG. 2 is a top view thereof;

FIG. 3 is a front view thereof; with rear view thereof being a mirror image thereof; and,

FIG. 4 is a left side view thereof, the right side view thereof being a mirror image of that which is shown.

1 Claim, 4 Drawing Sheets
